Application filed February 23, 1893. Serial No. 463,492. Term of patent 3½ years.

To all whom it may concern:

Be it known that I, CHARLES BARCLAY, of Lead, in the county of Lawrence and State of South Dakota, have invented and produced
5 a new and original Design for a Spoon, of which the following is a full, clear, and exact specification.

10 the figure represents a front view of a spoon embodying my new design.

At the outer end of the handle appears a

marine view including a sailing vessel. In the foreground is the shore, with the figure of an Indian prominent and represented as if 15 watching the vessel.

I claim—
